UNITED STATES PATENT OFFICE.

EDWARD C. COLSON, OF CHICAGO, ILLINOIS.

FUMIGATING APPARATUS.

SPECIFICATION forming part of Letters Patent No. 558,258, dated April 14, 1896.

Application filed May 20, 1895. Serial No. 549,858. (No model.)

To all whom it may concern:

Be it known that I, EDWARD C. COLSON, a citizen of the United States, residing in Chicago, in the county of Cook and State of Illinois, have invented a new and useful Improvement in Fumigating Apparatus, of which the following is a specification.

My invention relates to an apparatus for fumigating rooms or buildings and their contents.

The object of my invention is to provide a simple, inexpensive, and efficient apparatus for fumigating rooms, buildings, furniture, apparel, and other articles for the purpose of destroying disease germs.

In my invention the rooms or objects to be fumigated are subjected to the combined fumes of sulfur, tobacco, and burning charcoal, mixed with vapor of water, which I find effectually destroys all disease germs; and my invention consists in a fumigating apparatus comprising a charcoal-receptacle, a sulfur-receptacle, a tobacco-receptacle, and a water-receptacle, the sulfur, tobacco, and water receptacles being above the charcoal-receptacle, so as to be heated by the burning charcoal, and all inclosed within a suitable case or shell, forming a mixing-chamber, where the fumes rising from the burning charcoal, sulfur, and tobacco and the vapor arising from the heated water may all be intermingled and combined before being delivered from the apparatus into the room to be fumigated.

It further consists, in connection with these parts, of inlet and outlet conductor-pipes for connecting the apparatus with a room, so as to form a complete circuit or system of circulation between the apparatus and the room or building to be fumigated in cases where the apparatus is not placed directly in the room being fumigated.

It further consists in the novel combinations of parts and devices herein shown and described, and more particularly specified in the claims.

In the accompanying drawings, forming a part of this specification, and in which similar letters of reference indicate like parts in all the views, Figure 1 is a side elevation of an apparatus embodying my invention. Fig. 2 is a central vertical section. Fig. 3 is a

vertical section on the line 3 3 of Fig. 2. Figs. 4 and 5 are horizontal sections on lines 4 4 and 5 5, respectively, of Fig. 2. Fig. 6 is a detail perspective outline view of the grate turned upside down. Fig. 7 is a detail view of the combined leg and bolt, and Fig. 8 is a central vertical sectional view of a modification.

In the drawings, A and B are two shells, preferably of a cylindrical form and made of sheet metal, fitting one within the other with an open space C between them.

D and D' are upper and lower frame-rings, 65 preferably made of cast-iron and provided with flanges or shoulders d d to receive and hold in place the cylindrical shells A B when said rings are clamped together by the bolts E E, which are furnished each with integral 70 extensions E' to serve as the legs for supporting the apparatus. The leg-bolts E E' have offsets or shoulders E'' to bear against the lower frame-ring D'.

F is an annular sulfur-receptacle, G an 75 annular receptacle for the tobacco or tobacco stems, and H a central pot or receptacle for the water. The sulfur and tobacco receptacles F G are preferably formed of cast-iron and in one piece and are supported within the 80 cylinder B near the top thereof by a series of lips or projections f on the cast double annular pot F G, engaging an internal annular bead or shoulder b on said cylinder B, the open spaces f' f'' between the lips f f' serving 85 as the means of communication between the mixing-chamber K above the sulfur, tobacco, and water receptacles F G H and the charcoal-chamber L, and N is the dome or cover inclosing the mixing-chamber K.

The water-receptacle H is preferably formed in a separate piece from the annular casting F G. It is, however, preferably secured to this casting, this being conveniently done by the bail h, the ends h' of which are passed down through or below the inner peripheral edge g of said annular casting F G. The water-receptacle H has an annular shoulder h'' to support it on the annular casting F G and permit it to project down into and through 95 the central opening g' in said casting into the charcoal-chamber and be heated by the burning charcoal the same as the sulfur and tobacco receptacles.

The grate M may be of any suitable construction; but I preferably construct it of wire-netting, the most convenient way being to take a piece of wire-netting of a square form and shape it to fit within the cylinder B and at the same time turn its corners *m* down to form legs or supports for the grate. The grate M rests upon the bottom plate P of the apparatus, which rests upon the lower frame-ring D'.

R is the inlet-pipe leading from the lower portion of the room to be fumigated to the apparatus, and R' is the outlet-pipe leading from the apparatus to the room, as indicated in Fig. 1, so that a continuous circulation may be produced to and from the room through the apparatus, and S is the coupling or connecting pipe to which the inlet-pipe R is connected and which communicates with the upper flues C', preferably three in number, which communicate with the mixing-chamber K. The flues C' are formed in the open space C between the cylinders A B, the inner cylinder B being provided with openings or ports b', leading into the mixing-chamber, and the lower frame-ring D' having openings d' to receive the flue-stubs s on the coupling-pipe S. The coupling-pipe S extends preferably about two-thirds of the way around the cylinder, so that the three flues C' may be equally disposed about the circumference of the apparatus. The outlet or return pipe R communicates with the mixing-chamber K, the dome or cover N having a central nozzle or coupling N' at the top thereof.

C² C² are short flues also formed in the open space between the cylinders A B and communicating, through openings or ports b³ b³ in the inner cylinder B, with the ash-pit or chamber M' beneath the grate to supply fresh air to the burning charcoal to support the combustion and thus afford a continuous supply of carbonic-acid gas or products of combustion of the charcoal to mix in the mixing-chamber K with the fumes arising from the burning sulfur F' and tobacco G' and the vapor from the water H'.

To prevent undue heating of the inner cylinder B and injury to the apparatus, the space C between the cylinders A B not occupied by the flues C' C² is left free for the air to circulate through the same, this being effected by providing the upper and lower rings D D' with openings or perforations d³.

As shown in Fig. 1, the apparatus is set up outside of the room X to be fumigated; but by simply disconnecting the circulating-pipes R R' the apparatus may be placed inside the room and be there operated without further change, though ordinarily for operating inside a room I also remove the coupling or connecting-pipe S, so as to give more direct entrance to the inlet-flues C' for the air of the room.

In the modification shown in Fig. 8 the separate receptacle G for the tobacco is omitted, the tobacco or the juice or extract thereof be-

ing in this construction mixed with the water and placed in the water-receptacle H. This modified construction is more particularly designed for placing inside the rooms to be fumigated, and the pipes R R' and coupling S are also omitted. By this means it will be seen that the air from the room entering the mixing-chamber K is there subjected to the combined and intermingled fumes arising from the burning charcoal, sulfur, and tobacco mixed with the vapor of water, and thereby rendered effective in destroying disease germs. As the products arising from the burning charcoal enter the mixing-chamber in an annular series of individually-separated streams through the annular series of openings f' at the periphery of the mixing-chamber and are then deflected centrally or radially inward over the annular streams or masses of fumes arising from the annular sulfur-receptacle and from the annular tobacco-receptacle before reaching the central outlet, and are thus mixed, and must also pass directly over the central water-receptacle and become saturated or mixed with the vapor arising therefrom, it is obvious that the different vaporous products will become thoroughly intermingled and mixed together; and as the air from the room to be fumigated is led peripherally into this mixing-chamber and must pass radially over or across the annular streams or masses of fumes arising from the annular series of receptacles it follows that it must be thoroughly acted upon by all the different ingredients or agencies. It will be observed that as the products from the charcoal arise around the periphery of the sulfur-receptacle F, though the charcoal-receptacle is located below the receptacles F G H, the effect is that of four concentric receptacles having a common central outlet or discharge at the central opening n² of the dome or cover N, while at the same time the heat produced by the combustion of the charcoal is utilized as the means of heating the receptacles F G H.

I claim—

1. The fumigating apparatus herein shown and described and comprising in combination two cylinders or shells A, B, with open space C between them, two flanged frame-rings D D' having openings through the same, leg clamp-bolts E, sulfur-receptacle F, tobacco-receptacle G, water-receptacle H, grate M, dome or cover N, a mixing-chamber K between said dome M and said receptacles F, G, H, a charcoal chamber or receptacle L above said grate and below said receptacles F, G, and H, there being communications between said receptacles K and L, flues or communications C' leading to said mixing-chamber K from the room, a bottom plate P and flues or communications C² leading to the space beneath the grate, air-circulating pipes R R' and a coupling or connecting pipe S connecting the inlet-pipe R with the flues C', substantially as specified.

2. In a fumigating apparatus, the combina-

tion with an inclosing case or shell having a dome or cover N and bottom plate P, of a grate M near the bottom of said shell, annular sulfur-receptacle F, tobacco-receptacle G, 5 and a central water-receptacle H, said three receptacles extending across said shell near the top thereof above said grate and dividing the interior of said shell into a charcoal-chamber between said grate and receptacles and a 10 mixing-chamber between said receptacles and said dome or cover, said charcoal-chamber having a communication with said mixing-chamber, substantially as specified.

3. In a fumigating apparatus, the combination with an inclosing case or shell having a dome or cover N and bottom plate P, of a grate M near the bottom of said shell, annular sulfur-receptacle F, tobacco-receptacle G, 15 and a central water-receptacle H, said three receptacles extending across said shell near the top thereof above said grate and dividing the interior of said shell into a charcoal-chamber between said grate and receptacles and a 20 mixing-chamber between said receptacles and said dome or cover, said charcoal-chamber having a communication with said mixing-chamber, said dome or cover being provided with a central nozzle or outlet N', and said 25 mixing-chamber being also provided with an inlet flue or opening for the air, substantially as specified.

4. In a fumigating apparatus, the combination with two cylindrical shells A, B, having an open space between them and a dome or 35 cover N at the top, of a grate M near the bottom, an annular sulfur-receptacle F, an annular tobacco-receptacle G and a central water-receptacle H said receptacles together extending across said inner shell B near the top 40 thereof and dividing the interior of said shell into a mixing-chamber K above said receptacles and a charcoal-chamber B between said receptacles and said grate, and flues between said shells A, B, leading into said mixing- 45 chamber and into the space below said grate, substantially as specified.

5. In a fumigating apparatus, the combination with shells A B, of rings D D' furnished with openings through the same, grate M, 50 dome or cover N, annular receptacles F, G, central receptacle H, there being a charcoal-chamber above said grate below said receptacles and a mixing-chamber between said dome and said receptacles, communications 55 between said mixing-chamber and charcoal-chamber, and flues or communications leading into said mixing-chamber, substantially as specified.

6. In a fumigating apparatus, the combination with shells A B, of rings D D' furnished with openings through the same, grate M, dome or cover N, sulfur-receptacle F, central receptacle H, there being a charcoal-chamber above said grate below said receptacles and 60 a mixing-chamber between said dome and said receptacles, communications between said mixing-chamber and charcoal-chambers, and

flues or communications leading into said mixing-chamber, substantially as specified.

7. In a fumigating apparatus, the combination with a shell or case B having interior shoulders b, of a dome or cover N, a grate M extending across said shell near the bottom thereof, a central receptacle and an annular receptacle extending across said shell near 70 the top thereof and dividing said shell into a mixing-chamber above said receptacles and a charcoal-chamber below said receptacles, said annular receptacle having lips or projections f resting upon said shoulder b, and 75 provided with openings f' between said lips to form passages for communication between the charcoal-chamber and the mixing-chamber above said receptacles, substantially as specified. 80

8. In a fumigating apparatus, the combination of two concentric shells A, B, with frame-rings D D' furnished with flanges to receive and hold in place said shells, and combined leg and clamp bolts E E' extending between 90 said shells and through said rings and furnished with threaded nuts at the top to bear against the upper frame-ring, and offsets or shoulders to bear against the lower frame-ring and thus clamp the frame-ring and shells 95 together and form a support or leg projecting below said shells for the apparatus, substantially as specified.

9. In a fumigating apparatus, the combination with an inclosing shell B having dome or 100 cover N, receptacles extending across said shell near the top thereof, and a wire network grate M having integral turned-down corners n fitting the interior wall of said shell to form supports for the grate, said receptacles dividing the interior of said shell into a charcoal-chamber between said receptacles and said 105 grate, and a mixing-chamber above said receptacles, substantially as specified.

10. In a fumigating apparatus, the combination with two cylindrical shells A, B, having an open space between them and a dome or cover N at the top, of a grate M near the bottom, an annular sulfur-receptacle F, an annular tobacco-receptacle G and a central water-receptacle H said receptacles together 115 extending across said inner shell B near the top thereof and dividing the interior of said shell into a mixing-chamber K above said receptacles and a charcoal-chamber B between said 120 receptacles and said grate, and flues between said shells A, B, leading into said mixing-chamber and into the space below said grate, said dome or cover N having an outlet or nozzle N', and an outlet-pipe leading from said 125 mixing-chamber of said apparatus to the room, and a return-pipe leading from the room to the apparatus to produce a continuous circulation through the room and apparatus when the apparatus is outside the room, substantially as specified.

11. The combination with shells A B, of frame-rings D D', flues C' C², dome or cover N, grate M, mixing-chamber K, charcoal-

chamber L, an annular receptacle F and a central receptacle H, substantially as specified.

12. The combination with shells A, B, of frame-rings D D', flues C C², dome or cover N, grate M, mixing-chamber K, charcoal chamber L, an annular receptacle F and a central receptacle H, said shell B having

shoulder b and said annular receptacle F having lips f f' with spaces f' f' between, substantially as specified.

EDWARD C. COLSON.
